UNITED STATES PATENT OFFICE.

HENNING W. LUNDQUIST, OF ST. LOUIS, MISSOURI.

SLIDE-VALVE.

1,105,913.

Specification of Letters Patent,

Patented Aug. 4, 1914.

Application filed March 19, 1913. Serial No. 755,449.

To all whom it may concern:

Be it known that I, HENNING W. LUNDQUIST, a citizen of the United States, residing at St. Louis, in the State of Missouri, have invented certain new and useful Improvements in Slide-Valves; and I do hereby declare the following to be a full, clear, and exact description of the invention, such as will enable others skilled in the art to which it appertains to make and use the same.

This invention relates to new and useful improvements in internal combustion engine valves, and has for its object to provide a valve which will eliminate the usual troubles occurring from the use of the ordinary type of puppet valve.

In the ordinary construction of internal combustion engines it has heretofore been the practice to use a mushroom or puppet valve, and considerable inconvenience and trouble has been caused by the use of such valves, for the reason that the heat coming in contact with the metal causes the same to expand and warp, thus the proper seating 25 of the valve is not at all times insured. Another disadvantage of the puppet valve is that carbon gathering upon the same will prevent the proper seating and cause the gases contained within the cylinder to escape thereby losing considerable power from the operation of the engine.

The object of my invention is to eliminate the above named inconveniences caused by the use of the puppet valve and substitute a 35 valve wherein the deposit of carbon will be substantially eliminated.

Another object of my invention is to provide a valve which will perform the same functions of the puppet valve and still will not be prevented from warping by being surrounded by a suitable water jacket or other cooling means.

Still another object of my invention is to provide a valve which will operate similar 45 to the ordinary type of puppet valve and still combine the advantages of the puppet valve with those of the ordinary slide valve used in engines.

With the above and other objects in view, 50 I will now describe my invention in the following specification and accompanying drawings, in which—

Figure 1 is a longitudinal sectional view, 55 of a fragment of an internal combustion engine cylinder, showing my improved valve 60 and piston fixed to one side thereof; Fig. 2

is a transverse sectional view taken on line 2—2 of Fig. 1; Fig. 3 is a detail perspective view of the valve block used in my improved valve; and Fig. 4 is a view of the valve stem. 60

Referring to the drawings by characters of reference, 1 indicates the wall of an engine cylinder which is surrounded by the usual water jacket 2, and is provided with the usual opening 3 to receive the spark plug. 65 A piston 4, having a connecting rod 5 connected to the piston 6 and the usual piston rings 7 is slidably mounted within the cylinder of the motor.

A port 8 is provided at one side of the cylinder and is formed integral with the side walls thereof. This port 8 is provided with the enlarged opening 9, to which the manifold of the motor is adapted to be attached. The walls of the port are preferably water 70 jacketed, as indicated at 10, to keep the valve and the interior walls 11 of the valve casing cool. This interior wall is beveled, as shown at 12, to form the enlarged opening 13, the bevel 12 occurring at substantially 75 one-third the distance of the length of the valve seat. A bevel 14 is formed at the lower extremity of the valve seat and tapers inwardly toward the bottom. The lower end of the casing is extended, as shown at 15, in 80 the usual manner and is surrounded by a coil spring 16 which is adapted to coact with the annular flange 17 formed on the valve stem 18.

The usual cam shaft 20 is operably connected with the crank shaft of the motor and adapted to operate the cam 21, which works against the roller 22 on the vertical sliding rod 23. This rod 23 is adapted to slide through the sleeve 24, which is attached 90 to the cylinder of the motor. The upper end of the vertical sliding rod 23 is provided with a flange 25 and has a recess extending 95 thereinto for a short distance which is internally screw threaded, and adapted to receive a screw threaded bolt 19 that is provided with a flat head 19'. The head of this bolt 19 is adapted to engage the lower terminal of the stem 18 and force the stem upwardly during the operation of sliding the 100 valve.

The body portion of the block or valve, indicated by the numeral 26, is preferably tapered at its lower end, as indicated at 27. The wall then extends upwardly, as shown at 28, to within a short distance from its upper extremity, where it again tapers out.

wardly, as shown at 29, to form the enlarged head portion 30, which is adapted to work within the opening 13 of the valve casing. Intermediate the ends of the body portion 5 26 of the valve I preferably provide an elongated slot 31, which is adapted to register with the port 9 in the valve casing, and thereby open the port for the ingress or egress of gases from the cylinder. Between 10 the lower end of the valve of this body portion 26 and the slot 31, I preferably provide an aperture in which the screw 32 is adapted to be inserted, this screw 32 acting as a connection for the valve stem 18, which stem 15 18 is provided at its upper extremity with the enlarged portion 33.

The upper end of the opening 13 is closed by a detachable plate 34 that is mounted within the opening 13 and secured in position by means of bolts or other suitable fastening means 35 that are inserted through offset lugs 36 formed integral with the plate and have threaded engagement with the cylinder. An opening 37 is formed through 20 this plate 34 and registers with the opening 13 and the atmosphere so that accumulation of compression within the enlarged portion 13 of the valve seat is prevented and the possibility of the valve sticking is eliminated.

25 30 In operation the block is placed in position in the valve casing and connected up with the cam, as clearly described in the foregoing. It will be seen that when the cam comes up it will force the block upwardly and bring the recess 31 into registration with the recess 8, thereby opening the valve for use. Upon the cam descending, the spring 16 will force the valve downwardly and prevent any escape of gases from 35 40 the cylinder.

While in the foregoing I have shown and described the preferred embodiment of my invention, I wish it to be understood that I may change the specific arrangement of 45 parts without in any way departing from the spirit and scope of my invention.

Having thus fully described my invention, what I claim is:

1. In combination with an internal combustion engine cylinder, a valve casing, said valve casing having a recess therein, the upper end of said recess being enlarged, a block 50 55 slidably within the recess, the upper end of said block being enlarged to conform to the shape of the recess, means to move said block vertically, and the upper wall of the recess provided with a port communicating with

the atmosphere to prevent the accumulation of pressure against the enlarged end of the block. 60

2. The combination with the cylinder of an internal combustion engine of a valve casing carried by said cylinder and having a recess therein, ports extending transversely through the valve casing and communicating 65 with the recess, said recess enlarged at its upper terminal, a block slidably mounted within the recess, said block enlarged at its upper terminal to conform to the shape of the recess and having an aperture intermediate 70 its ends adapted to register with the ports, means for reciprocating the block whereby the port is brought into registration with the port in the casing and means for preventing accumulation of pressure adjacent the enlarged end of said block within 75 the enlarged portion of said recess. 75

3. The combination with the cylinder of an internal combustion engine, of a valve casing carried by said cylinder and having a recess therein, a block slidably mounted within the recess, said block having its upper terminal enlarged, said recess having its upper terminal enlarged to conform to the shape of said block, a port extending transversely through the casing and communicating with the recess, an aperture intermediate the ends of said block adapted to register with the port, the upper wall of the recess having a port therein communicating 90 with the atmosphere to prevent the accumulation of pressure against the enlarged end of the block and means for reciprocating said block. 85

4. The combination with the cylinder of an internal combustion engine of a valve casing carried thereby and having a recess therein, said recess enlarged at its upper terminal and reduced at its lower terminal, a block slidably mounted within the recess 95 and having an aperture therein intermediate the ends thereof, said block enlarged adjacent its upper terminal and reduced at its lower terminal to conform to the shape of the recess and means for preventing the accumulation of pressure against the enlarged end of said block within the enlarged portion 100 of the recess. 105

In testimony whereof I affix my signature in presence of two witnesses.

HENNING W. LUNDQUIST.
